UNITED STATES PATENT OFFICE.

EDWARD J. BROOKS, OF EAST ORANGE, NEW JERSEY, ASSIGNOR TO E. J. BROOKS & CO., OF NEW YORK, N. Y.

METALLIC SEAL.

SPECIFICATION forming part of Letters Patent No. 286,775, dated October 16, 1883.

Application filed January 2, 1883. (No model.)

To all whom it may concern:

Be it known that I, EDWARD J. BROOKS, a citizen of the United States, residing at East Orange, in the State of New Jersey, have invented a new and useful Improvement in Metallic Seals, of which the following is a specification.

This invention relates to the construction of "tin and eyelet" seals for securing the doors 10 of railway freight-cars, and for like uses.

Heretofore "tin and eyelet" seals, so termed, have consisted of narrow strips of tin-plate or "tin" and the sheet metal "eyelets" of commerce, the ends of the former being provided 15 with holes to receive the stems of the eyelets. These seals are extensively used, owing to their "cheapness" in first cost, but sometimes lose this advantage in use, especially in winter, owing to the loss of the small and slippery eyelets from between cold or gloved fingers. Moreover, to align the holes in the respective ends 20 of the tin strip, and insert the small eyelet and keep it in place until it is pressed, involves no little skill, and is frequently slow work, owing to inexperience, dark, or cold, and, in addition 25 to this, carrying and handling two distinct parts for each seal is inconvenient, and to properly insert the eyelet in a lettered or colored strip, so that its lettered or colored face shall 30 be outside, is frequently difficult in sealing cars at night or in a blinding storm.

In my specifications forming part of Letters Patent No. 246,068, dated August 23, 1881, and No. 260,279, dated June 27, 1882, I describe and claim two forms of "lead-and-tin" seals, having their parts permanently united 35 in the process of manufacture, and set forth some of the advantages of this mode of making seals. I have discovered that I can apply 40 the same principle with additional advantages in the manufacture of what I have termed "tin-and-eyelet" seals, and have so applied said principle, my present invention consisting in a tin-and-eyelet seal composed of a strip of tin 45 or equivalent sheet metal having a hole in each end, and an eyelet of lead or equivalent soft metal cast fast in one of said holes, and having its stem fitted to the other of said holes as a new article of manufacture.

As compared with other tin and lead seals

my said tin-and-eyelet seal is adapted to be made exceedingly light, and therefore cheaper, less power is required to press it, and the orifice of the eyelet receiving the eyeleting-nipple of the press insures accurately locating 55 the eyelet in the seal-press, so that in the pressing operation its head or rim may be distinctly stamped with lettering or distinguishing marks, notwithstanding its small size. At the same time it is adapted to be pressed, by means 60 of ordinary eyeleting-pliers, like other tin-and-eyelet seals. As compared with these it is more easily pressed, and the strip ends cannot be burst by the expansion of the eyelet, owing to the soft metal of the latter. It is also 65 adapted to be provided in the sealing or eyeleting press with lettering or distinguishing marks impressed in the soft metal, as aforesaid, and is adapted to be made complete from 70 tin sheets and lead pigs or scraps of tin and lead in one factory, besides its freedom from the special objections to tin-and-eyelet seals as heretofore made, and the objections common to seals which consist of two distinct parts which must be put together, often under 75 great disadvantages, preliminary to pressing each seal, as hereinbefore set forth.

In the sheet of drawings accompanying this specification, and forming part thereof, Figure 1 is a perspective view of a tin-and-eyelet seal 80 constructed according to this invention as it comes from the factory. Fig. 2 is an edge view thereof, partly in section, showing it ready for the press; and Fig. 3 is a like view of the same pressed. Figs. 4 and 5 are fragmentary sectional views, and Fig. 6 a corresponding face view of another substantially-similar seal, illustrating a modification; and Fig. 7 is a face view of a third seal, illustrating another modification of the same invention. 85 90

Like letters of reference indicate corresponding parts in the several figures.

In each form my said new seal consists of a "strip," S or S² or S³, of sheet metal, preferably ordinary tin-plate (tin) of commerce, and 95 an eyelet, E or E² or E³, of soft metal, preferably lead, permanently united with each other in the act of casting the latter, said strip having the customary punched holes, a b, in its respective ends, the former occupied by the hol- 100

low stem or tube of the eyelet, which, being cast therein, tightly fills it, and sufficiently overlaps the surrounding metal of the strip to preclude accidental separation. In so casting 5 the eyelet a mold may be used in the manner and of the construction substantially set forth in my said specification forming part of Letters Patent No. 260,279, and illustrated by Fig. 7 of its drawings, with a central pin or wire 10 fixed or removable as an axial core.

The eyelet E may be as small, or nearly as small, as the sheet-metal eyelets heretofore used, as illustrated by Figs. 1 to 3, or, as illustrated by Figs. 4 to 6, the eyelet E² may be cast 15 with a rim, c, sufficiently wide to receive suitable distinguishing marks or lettering—such as the initials of a railroad arranged in a circle—as shown in Fig. 6. The strip S may likewise be of plain tin, which Figs. 1 to 3 may illustrate; 20 or the face of the strip S² may be of a distinguishing color or tint, (red for one road, for example, and blue for another, or yellow for one direction of travel and green for another, or any like arbitrary or appropriate contrasts,) 25 which Figs. 4 to 6 may illustrate; or the face of each strip S³ may be lettered and numbered, or either lettered or numbered, by printing the same, or otherwise, as illustrated by Fig. 7.

Fig. 7 shows a new and preferred arrange-

ment of such strip-marks d d², a complete mark 30 for each side or exposure of the face of the bent strip being provided by duplicating the same at the respective ends of the strip. The eyelet being cast in insures the proper exposure of the "face," besides facilitating the preparation of the seal for the press, as hereinbefore set forth. The eyelet E³ (shown in Fig. 7) may be similar to either of the others, E or E².

I am aware that an eyelet of sheet metal integral with a sheet-metal sealing-strip has 40 been proposed. This forms no part of my invention, and, together with the combination, with a sheet-metal sealing-strip, of a separate sheet-metal eyelet, such as are commonly used, is hereby disclaimed as old. 45

I claim as my invention—

As a new article of manufacture, an improved tin-and-eyelet seal, composed of a strip 50 of sheet metal having holes a b in its respective ends, and an eyelet of soft metal cast fast within the said hole a, with its stem projecting from the back of the strip and fitted to the said hole b, as herein specified, for the purposes set forth.

EDWARD J. BROOKS.
